PARFAIT CUP

Steve Fotos, Fort Lee, N.J., assignor to Multi Molds International, Inc., New York, N.Y., a corporation of New York

Filed Feb. 20, 1962, Ser. No. 68,907

Term of patent 14 years

(Cl. D44—9)

I claim:

The ornamental design for a parfaits cup, as shown.
